BUILDING PANEL

Robert R. Fink, Niles, Mich., assignor to Kawneer Company, Niles, Mich., a corporation of Delaware

Application August 5, 1955, Serial No. 37,325

Term of patent 14 years

(Cl. D54—2)

Fig. 1

Fig. 2

Fig. 1 is a perspective view of a building panel showing my new design; and

Fig. 2 is a top plan view thereof.

The design is of arbitrary overall length.

I claim:

The ornamental design for a building panel, substantially as shown and described.
